DESIGN FOR BATHING TRUNKS

Theodore R. Upland, San Francisco, Calif., assignor to Gantner & Mattern Company, San Francisco, Calif., a corporation of California

Application November 8, 1937, Serial No. 72,691

Term of patent 7 years

To all whom it may concern:

Be it known that I, Theodore R. Upland, a citizen of the United States, residing in the city and county of San Francisco, State of California, have invented a new, original, and ornamental Design for Bathing Trunks, of which the following is a specification, reference being had to the accompanying drawing, forming a part thereof.

In the drawing Fig. 1 is a front perspective view of the trunks in the form as worn.

Fig. 2 is a front view of the bathing trunks shown in Fig. 1.

In the drawing the dotted lines represent stitching.

The rear of the trunk or upper portion of the garment is of continuous fabric, the stitching at the waist is continuous around the rear; the stitching at the thigh termini continues to the rear to the crotch portion and continues as indicated to join the crotch and trunk portions.

I claim:

The ornamental design for bathing trunks, as shown and described,

THEODORE R. UPLAND.
